(57) **CLAIM**

I claim the ornamental design for a conveyor transfer guard, as shown and described.

DESCRIPTION

FIG. 1 is a perspective view of a conveyor transfer guard, showing my new design;

FIG. 2 is a front elevational view thereof, the rear being identical;

FIG. 3 is a side elevational view thereof, the opposite side being identical;

FIG. 4 is a top plan view thereof; and,

FIG. 5 is a bottom plan view thereof.

The broken lines in the figures are included for the purpose of illustrating portions of the conveyor transfer guard and forms no part of the claimed design.

The transfer guard is shown with a symbolic break in its length in FIGS. 1 and 3-5. The appearance of any portion of the article between the break lines forms no part of the claimed design.
